UNITED STATES PATENT OFFICE.

DANIEL F. MORIARTY, OF SOUTH MERIDEN, CONNECTICUT.

LAMP-CORD-ADJUSTING CLAMP.

1,321,660.

Specification of Letters Patent. Patented Nov. 11, 1919.

Application filed April 5, 1919. Serial No. 287,672.

To all whom it may concern:

Be it known that I, DANIEL F. MORIARTY, a citizen of the United States, and a resident of South Meriden, county of New Haven 5 and State of Connecticut, have invented a new and Improved Lamp-Cord-Adjusting Clamp, of which the following is a full, clear, and exact description.

This invention relates to a lamp cord adjusting button. More particularly it relates to an adjusting clamp applicable to incandescent lamp cords for shortening or lengthening the lamp cord obviating the necessity of tying knots in the cord and otherwise 15 damaging it.

Electric light lamp cords which usually depend from the ceiling of a room necessarily need to be shortened and lengthened out at times to make their use more convenient and prevent the electric light or fixture 20 from becoming inconveniently in the way.

It is a purpose of my invention to provide a simple form of clamping device or adjusting button which may be mounted upon a 25 lamp cord and left there indefinitely for the purpose of adjusting the length of the cord.

A constructional purpose of my invention is to provide a simple form of lamp cord or 30 adjusting button comprising two separable clamping members held together by a screw and fitted with a yieldable spring means to prevent damage to the cord when the button or clamp is slipped or adjusted on said cord.

It is also a purpose of this invention to 35 provide a clamp with the above utility characteristics which will be comparatively inexpensive to manufacture, simple in its application and incapable of getting out of order.

With the above and other objects in view 40 the invention has relation to a certain shape and form of elements, and combination one with the other, and their mode of use. A description of the invention is had in the following specification, pointed out in the 45 appended claims and illustrated in the accompanying drawings, wherein:

Figure 1 shows the adjusting clamp applied to a lamp cord.

Fig. 2 and Fig. 3 respectively illustrate the 50 assembled clamp in side elevation and in end elevation.

Fig. 4 shows a cross sectional view of the clamp.

Figs. 5 and 6 show the two separable clamp jaws apart one from another. 55

Fig. 7 illustrates a modified form of clamp.

Figs. 8 and 9 illustrate end elevations of 60 cord adjusting clamps provided with variously shaped cord receiving channels.

Fig. 10 shows a knurled thumb screw which may be used in clamping the two separable jaws together.

Referring more particularly to the drawings, the numerals 1 and 2 respectively point 65 out an upper and lower clamp jaw member.

The clamp members are provided with a tongue 3 and groove 4 joinder means. The tongue and groove are adapted to register one with the other thus alining the clamp 70 jaw members one with the other and in a correctly engaging relation. A tapped or

screw threaded hole 5 is formed in the jaw member 2 and a clamp screw receiving bore 6 is formed in the other member. A clamp 75 screw 7 is inserted in the bore and screw threaded into the tapped hole 5. The clamp jaw 1 is provided with a groove 8 cut in the outer face of the jaw and adapted to receive a flat leaf spring 9 which is provided with 80

a hole and placed upon the screw and thus retained in position within the slot. The base of the groove 8 is arcuate in contour as designated by the numeral 10. This leaves 85 open space between the base of the groove and the surface of the spring. Cord receiving channels 11 are formed in the clamping device, and are preferably cylindrical in shape. Two of these channels or openings

will be provided such that the lamp cord 90 may be inserted in one, folded and looped down and passed back through the other. These holes or cord receiving openings will be enlarged at each end or countersunk in form thus beveling off and cutting away any 95 shape edges which would tend to chafe or damage the cord. This particular construction is pointed out by the numeral 12 which points to the easy curved contour comprising a very large opening in the end of the clamp device and tapering down to the normal size 100 of the cord openings 11. The above de-

scription covers the preferable form of the clamping device and shows the tongue and groove means formed parallel with the cord receiving holes. This insures simplicity and 5 convenience in manufacture.

The Figs. 7, 8 and 9 illustrate modified designs of this cord adjusting button or clamp. Fig. 7 shows the tongue and groove joinder means formed in the clamping members transversely to the cord receiving holes. 10 Figs. 8 and 9 illustrate different shapes and forms of cord receiving openings. This will adapt the device to fit any standard shapes of cords.

15 The knurled thumb-adjusting clamp screw 7 illustrated may be employed in preference to the screw shown in connection with the illustrated clamp. This form of screw will render it unnecessary to always have a screw 20 driver on hand to adjust the device.

After the right length of lamp cord is obtained the screw will be screwed downwardly into the jaw 2 which brings the associate jaw members tightly one against the 25 other. The leaf spring 9 flexes sufficiently to prevent the cord from being unduly squeezed or damaged in case the clamp is too tightly applied against the cord. This spring will also permit the jaw members to yield 30 slightly one from the other thus enabling one to slip the clamp along the cord without always unloosening the screw.

This form of cord adjusting button or 35 clamping device is simple in operation and convenient to apply and will not get out of working order.

Having thus described my invention, what I claim as new, and desire to secure by Letters Patent is:

40 1. A lamp cord adjusting device comprising in combination, two separable halves joined together, a clamp screw adapted to

clamp the separable halves together, and a spring coöperating with the screw for rendering the separable halves yieldable one on 45 the other so that the lamp cord may be slipped through the device.

2. In a lamp cord adjusting device, a pair of clamp jaws, said jaws fitted with tongue and groove joinder means, a flat leaf spring 50 applied to one of the jaws, and a screw engaging the jaws and the spring.

3. In a lamp cord adjusting button or clamping means for application to an incandescent lamp cord for adjusting the 55 length of said cord, a pair of clamp members with cord receiving openings, a clamp screw adapted to clamp and hold together the clamp members, and a spring arranged to press against the screw to make yieldable 60 the clamping action of the clamp members.

4. In a lamp cord adjusting button or clamping means of the character described for application to an incandescent lamp cord for adjusting the length of said cord, a pair 65 of clamp jaws provided with cord receiving openings and provided with tongue and groove joinder means, a groove formed in the outer surface of one of the clamp jaws, a flat leaf spring placed in the groove, and 70 a clamping screw engaging the leaf spring and the jaws for clamping said jaw members together against the yieldable spring action of the leaf spring.

5. In a lamp cord adjusting button or 75 clamping means, a pair of clamp members with cord receiving openings which are counter-bored and rounded out at the ends for protection to the cord, tongue and groove joinder means, a groove formed in the face 80 of one of the clamps, a clamp screw engaging the spring and the clamp jaws for clamping the jaw members together.

DANIEL F. MORIARTY.
